W. BARRON ET AL.

ANNEALING POT

Filed Sept. 5, 1922

Inventors:
William Barron &
Charles A. Barron
by Gilbert H. Jenner,
Attorney.

UNITED STATES PATENT OFFICE.

WILLIAM BARRON AND CHARLES A. BARRON, OF PRESTON, ENGLAND.

ANNEALING POT.

Application filed September 5, 1922. Serial No. 586,294.

To all whom it may concern:

Be it known that we, WILLIAM BARRON and CHARLES A. BARRON, subjects of the King of Great Britain, residing at Preston, 5 in the county of Lancaster, England, have invented certain new and useful Improvements in Annealing Pots, of which the following is a specification.

This invention relates to pots in which 10 metals are annealed or otherwise treated by heat without becoming tarnished, and it consists in the novel construction and combination of the parts hereinafter fully described and claimed.

15 The drawing shows a vertical section through an annealing pot constructed according to this invention.

The pot *a* is of any approved construction, and it has a removable lid *c*. The lid 20 preferably has a flange *c*¹ which projects downwardly into sand *p* in a groove *a*² around the top edge of the pot, so as to make a gas-tight joint.

25 A lifting plate *i* rests on the bottom of the pot, and is provided with a lifting rod *i*² having an eye *i*¹ at its top. A hood *h* is arranged inside the pot to cover the articles being treated. This hood rests on the lifting plate, and its top has a hole *j*² 30 through which the eye projects.

A receptacle *j* for charcoal *k*, or other purifying agent, is provided around the said eye, and *j*¹ are perforations in that portion of the top of the hood which forms the bottom of the said receptacle. The lid *c* has a tubular projection *l* secured to it, and provided with a passage *m*¹ for gas, and a conical outer surface *m*. A pipe *n* for the admission of a non-oxidizing gas, such as ordinary illuminating gas, is secured to a weight *o* which has a conical chamber adapted to fit closely over the conical projection so as to make a gas-tight joint.

The weight and gas pipe are preferably removed during the heating process. The 45 charcoal in the receptacle *j*, coupled with the natural issue through the perforations of the gases formed in the hood as the result of the heating, prevents any ingress of air to the hood during the heating operation. When the heating is completed the weight and gas pipe are placed in position, and a supply of non-oxidizing gas is connected to the pipe. The space or chamber formed between the hood and the sides of 50 the pot and its lid is filled with the non-oxidizing gas, which is drawn into the hood through the charcoal, or other purifying agent in the receptacle *j*, as the cooling proceeds. The metal articles being treated or 55 annealed inside the hood are in this manner kept bright and are prevented from oxidizing.

What we claim is:

1. An annealing pot provided with a lid, 60 a lifting plate resting on the pot, a hood resting on the said plate and forming a gas chamber with the pot and lid, and means for admitting a non-oxidizing gas through the said chamber into the hood. 70

2. An annealing pot as set forth in claim 1, and having at the top of the said hood a receptacle for a purifying agent having a perforated bottom which permits the passage of gases between the interior of the 75 hood and the said chamber.

3. An annealing pot as set forth in claim 1 and having a conical tubular projection on its lid, and an inlet pipe for the gas provided with a weight having a conical chamber which fits over the conical projection and forms with it a gas-tight joint. 80

In testimony whereof we affix our signatures.

WM. BARRON.
C. A. BARRON.
